UNITED STATES PATENT OFFICE

2,480,734

SEWING MACHINE

Richard K. Hohmann, Jamaica, N. Y., assignor
to Sears, Roebuck and Co., Chicago, Ill., a corporation of New York

Original application July 18, 1942, Serial No. 451,422, now Patent No. 2,430,932, dated November 18, 1947. Divided and this application April 4, 1947, Serial No. 739,436

4 Claims. (Cl. 112—221)

1

This application is a division of my prior application, Serial No. 451,422, filed July 18, 1942, which has matured into Patent No. 2,430,932 dated November 18, 1947, and discloses and claims a sewing machine characterized in part by the incorporation in the hollow sewing machine head or frame of sewing machine parts or adjuncts which heretofore have customarily been external to the head or frame. The object of the invention claimed herein is to provide an improved driving connection between a motor mounted on the base portion of the sewing machine frame and the needle bar actuating shaft mounted on the upper portion of the frame and including a guiding belt within the hollow standard portion of the frame. While the invention claimed herein is not limited to use in a sewing machine having the special characteristics disclosed and claimed in said Patent 2,430,932, it is of a special utility in a sewing machine characterized as above mentioned.

The various features of novelty which characterize my invention are pointed out with particularity in the claims annexed to and forming a part of this specification. For a better understanding of the invention, however, its advantages and specific objects attained with its use, reference should be had to the accompanying drawing and descriptive matter in which I have illustrated and described a preferred embodiment of the invention.

Of the drawings:

Fig. 1 is a side elevation of a sewing machine head partly broken away and in section;

Fig. 2 is a section on the line 2—2 of Fig. 1;

Fig. 3 is a partial section on the line 3—3 of Fig. 1; and

Fig. 4 is a perspective view illustrating details of the drive mechanism.

In the accompanying drawings I have illustrated the use of the improvements disclosed and claimed herein, in a convertible sewing and darning machine of known type adapted for mounting in a drop head sewing machine cabinet, but the said improvements claimed herein are not restricted to use in sewing machines of said type.

In the preferred form illustrated, the sewing machine frame comprises a main frame casting, which includes a pedestal portion A, a standard A¹ extending up from the pedestal portion, an arm A² extending horizontally away from the upper end of the standard and terminating at a distance from the latter in a needle head A³, and a cylinder arm A⁴ extending horizontally away from one side of the pedestal beneath the arm

2

A². Detachably secured to the pedestal portion of the main frame casting is a base member A⁵ comprising a flat bottom portion, and an uprising rim portion displaced from the cylinder arm A⁴, and comprising portions at opposite sides of the latter and a connecting end portion remote from the pedestal. A removable flat work bed part A⁶ may be supported by the cylinder arm A⁴ and the rim of the base member A⁵, to adapt the machine for ordinary flat sewing operations, or may be removed to facilitate sewing, darning and repairing operations on tubular work pulled over the free end of the cylinder arm A⁴.

The hollow standard A¹ and horizontal arm A² portions of the frame are relatively larger in transverse cross section than has been customarily heretofore, and are adapted to house mechanism parts heretofore customarily mounted externally of the frame. The sewing machine frame shown in the drawing is also characterized by its formation with a top opening A⁷ which extends horizontally for substantially the full length and width of the arm A² and across the upper end portion of the standard A¹. The opening A⁷ is normally closed by a readily removable cover B, which is advantageously provided with a spring lever or other yielding retaining device B¹ adapted to releasably secure the cover in place. The standard is also formed with an opening A⁸ in its front wall normally closed by a door or cover member C which has an inwardly extending arm C¹ pivoted to the frame at A⁹. The opening A⁸ is provided to give access to, and to facilitate the use of a bobbin winding mechanism not claimed or described in detail herein, but devised by me and fully disclosed and claimed in said parent application.

The horizontal needle bar actuating shaft D which forms the main driving shaft of the sewing machine is mounted in the lower portion of the chamber space in the arm A², and extends across the upper end of the chamber space in the standard A¹. The under bed sewing machine mechanism comprises a hook shaft E mounted in the cylinder arm A⁴ and carrying a rotary hook E¹ at its front end. A vertically disposed shaft F journalled in the standard A¹ is gear connected at its ends to the shafts D and E and thus forms means through which the driving shaft D rotates the hook shaft E. As shown, the sewing machine includes a feed mechanism comprising a pair of levers G extending upward through the standard A¹ from about the level of the shaft E, and operatively connected at their upper ends to the driving shaft D. The said feed mechanism forms no part

of the present invention and may be, and as shown is, identical with that disclosed in my prior Patent 2,247,379 of July 1, 1941, and need not be further described herein. It is noted, however, that the manually adjustable lever G^1 which by its angular adjustment determines the direction of the work feed and the length of the stitches formed, extends through a slot formed for the purpose in the central portion of the door C , and through a portion A^{10} of the frame casting which extends directly back of the cover C when the latter is in its closed position.

The driving shaft D is rotated in normal operation by an electric motor H mounted in the pedestal portion of the frame and connected to the shaft D by a belt H^1 . The belt H^1 extends about a driving pulley H^2 on the shaft of the motor H and a pulley H^3 surrounding and adapted to be releasably clutched to the driving shaft D as hereinafter described. A guide pulley or idler H^4 adjustably mounted in the standard A^1 engages the belt and keeps it taut. The pulleys H^3 and H^4 and belt H^1 are located within the space surrounded by the unitary, standard forming, portion of the main frame casting, which is formed with an opening A^{11} through which the idler H^4 may be adjusted and through which the belt H^1 may be manipulated in belt replacing operations. The opening A^{11} is normally closed by a removable cover part a .

As collectively shown in Figs. 1, 2 and 3, the pulley H^3 surrounds an elongated hub portion I^1 of the hand wheel I , and is normally secured to said hub portion by set screws I^2 . The body portion of the hand wheel I is external to the frame, and its elongated hub I^1 extends loosely through an opening A^{12} formed in the side of the standard and substantially concealed and closed by the hand wheel I . The pulley H^3 and hand wheel I are releasably clamped to the driving shaft D for sewing operations, or are freed to rotate about the then stationary shaft D in bobbin winding operations, by angular adjustments relative to the shaft D , of a clamping nut J screwed on the threaded inner end of the shaft D . When the nut J is rotated in the clamping direction relative to the shaft D , the hub I^1 is clamped between an outwardly extending flange portion of a member K surrounding the shaft D and rigidly secured thereto by set screws and a washer L which is interposed between the head of the clamping screw J and the outer side of the hand wheel I . The outer portion of the bore of the nut J is enlarged to receive the head d of a screw threaded into the end of the shaft D . The screw head d is larger in diameter than the shaft D and is provided to prevent the nut from being inadvertently entirely screwed off the shaft D .

To provide a suitably long bearing for the pulley H^3 and hand wheel I , and to permit their movement to the right, as seen in Fig. 1, to facilitate replacement of the driving belt H^1 , I make use of a bearing sleeve M which surrounds both the elongated hub portion K^1 of the member K and the aligned tubular body of the clamping nut J . Longitudinal slots M^1 formed in the inner end of the member M receive spline ribs K^2 carried by the hub portion K^1 . As shown, the member M is also formed at the outer end with longitudinal slots M^2 which receive lateral projections L^1 from the washer L . The outer surfaces of the parts L^1 form extensions of the cylindrical outer surface of the member M and elongate the bearing surface from the hub I^1 when the clamping screw J is backed off and the parts I and H^3 are moved

relative to the shaft D into their dotted line positions shown in Fig. 3. Such displacement of the pulley H^3 facilitates manipulations of the belt effected in the course of belt replacement through the frame opening A^{12} . The member M also provides a spline connection between the clamping washer L and the part K and shaft D which facilitates the clamping of the pulley H^3 to said shaft.

At its inner side, the pulley H^3 is provided with a cylindrical flange H^5 which during the bobbin winding operation serves as a driving roll engaged by and rotating a friction wheel N . The latter is secured on one end of a bobbin winding spindle or shaft N^1 which has its opposite end bifurcated to enter the central passage of a bobbin which may be detachably and frictionally secured to said spindle. The spindle N^1 is journalled in a bearing block N^3 carried by the upper end of an arm O which has its lower end journalled on a pivot O^2 anchored in a supporting member P . The latter is vertically disposed in the standard A^1 and adjacent its lower end is pivoted on a pivot pin P^1 having a threaded extension anchored in a frame casting lug or projection A^{13} . The shaft N^1 , and pivot pins O^2 and P^1 are all parallel to the driving shaft D .

The supporting means for the spindle N^1 to which reference has just been made, form part of the mechanism by which the pulley N may be adjusted between positions within the hollow standard A^1 in which it does and does not operatively engage the flange H^4 of the pulley H^3 , so as to be rotated by the latter, and through which the spindle may be moved out of the standard A^1 through the opening A^8 to facilitate the mounting of a bobbin on, and its removal from the bifurcated end of said spindle N^1 , as is fully disclosed in my said prior application.

To separate the hand wheel I from the pulley H^3 and shaft D preparatory to their removal from the frame, it is necessary only to loosen the set screws I^2 , remove the screws d , and screw the clamping nut member J off of the shaft D . The hand wheel I and bearing sleeve member M may then be removed from the machine, and thereafter the driving shaft D may be displaced in its bearings, to the left as seen in Fig. 1, far enough to clear the pulley H^3 , and the latter may then be moved upwardly out of the arm A^2 through the opening A^7 . The assembly of the above mentioned parts may be effected by operations the reverse of those just mentioned.

The separable hand wheel I and driving pulley H^3 are formed and associated with the driving shaft D , in a practically simple and effective manner and are characterized by the relative ease with which they may be assembled and disassembled. The detachable mounting of the pulley H^3 on the hub of the hand wheel I , and the provisions made for disconnecting them from the drive shaft D , make it possible to locate the hand wheel outside, and the pulley within the frame, while permitting the frame opening A^{12} through which they are connected, to be substantially smaller in diameter than either the pulley or the hand wheel.

While in accordance with the provisions of the statutes, I have illustrated and described the best form of embodiment of my invention now known to me, it will be apparent to those skilled in the art that changes may be made in the form of the apparatus disclosed without departing from the spirit of my invention, as set forth in the appended claims and that in some cases certain

features of my invention may be used to advantage without a corresponding use of other features.

Having now described my invention, what I claim as new and desire to secure by Letters Patent, is:

1. In a motor driven sewing machine the combination with a frame including a base portion, a hollow standard and a hollow arm connected at one end to the upper portion of the standard and extending away from one side of the latter, said frame being formed with an opening at the side of said standard opposite to the first mentioned side and in register with said hollow arm, a needle bar shaft within and extending longitudinally of said arm through said standard and opening, a driving motor mounted in said base portion, a driving connection between said motor and shaft comprising a pulley member mounted on said shaft adjacent and at the inner side of said opening, a hand wheel mounted on said shaft adjacent and at the external side of said opening, means extending through said opening detachably connecting said pulley and hand wheel and clamping means including an actuating element accessible for adjustment at the outer side of said hand wheel for releasably clamping said pulley and hand wheel to said shaft.

2. A sewing machine as specified in claim 1, including an inner clamping member secured to said shaft, a bearing sleeve interposed between said shaft and said hand wheel and pulley and in splined relation with said inner clamping member and an outer clamping member in splined relation with said sleeve.

3. A sewing machine as specified in claim 1, including an inner clamping member secured to said shaft, a sleeve bearing interposed between said shaft and said hand wheel and pulley and comprising a tubular member in splined relation with said inner clamping member and including spaced apart outer end portions extending longi-

tudinally of said shaft, and comprising a washer forming an outer clamping member and parts having their outer ends connected to said washer and extending longitudinally of said shaft and in interlocking relation with the outer end portions of said sleeve bearing.

4. A sewing machine as specified in claim 1 which includes a sleeve bearing interposed between said shaft and said hand wheel and pulley and includes tubular inner and outer end members surrounding said shaft, said inner end member being secured to said shaft and including an outwardly extending flange at the inner end of said sleeve bearing which serves as an inner clamping member, and said outer end member comprising an outwardly extending flange at the outer end of said sleeve bearing which serves as an outer clamping member, said sleeve bearing and inner end member comprising side by side portions extending longitudinally of the shaft and interlocking to form a splined connection between said inner end member and sleeve bearing, and said outer end member and sleeve bearing comprising side by side portions extending longitudinally of said shaft and interlocking to form a splined connection between said outer end member and sleeve bearing, said outer end member being moved toward said inner end member by the adjustment of the actuating element to clamp said pulley and hand wheel to said shaft.
